UNITED STATES PATENT OFFICE.

EDMUND W. QUINCY, OF PEORIA, ILLINOIS, ASSIGNOR OF ONE-HALF HIS
RIGHT TO JOHN H. HALL, OF SAME PLACE.

IMPROVEMENT IN CORN-HARVESTERS.

Specification forming part of Letters Patent No. 140,305, dated June 24, 1873; application filed
March 22, 1873.

To all whom it may concern:

Be it known that I, EDMUND W. QUINCY, of the city of Peoria, in the county of Peoria and in the State of Illinois, have invented an Improvement in Machines for Picking or Gathering Corn, Husking and Hackling the Husk; and I do hereby declare that the following is a full, clear, and exact description thereof, reference being had to the annexed drawings making a part of this specification, in which like letters of reference refer to like parts, and in which—

Figure 1 represents a side elevation of the machine as attached to a common wagon, showing a section (vertical) of the husking and hackling box and rollers; Fig. 2, a plan, with the edge of the platform broken off to show gearing of driving-shaft with the pinions of the chain-pulleys; Fig. 3, rear elevation of outer half of pulley-gearing or driving mechanism; Fig. 4, vertical section through the roller-box *p* and longitudinally through the holes *d d* in the platform *B*.

This invention consists in a peculiar construction and combination of devices, as hereinafter described and pointed out in the claims.

A in the drawings represents the wagon; *B*, the platform, which is attached, in an inclined position, to the wagon by a brace, *C*, passing across the wagon sides, and supporting the platform from beneath. The brace is firmly held by clamps *a a* beneath the wagon. The platform may be about nine feet along, divided centrally and longitudinally by a slot or slit, *b*, about one and a half inch wide, running about two-thirds up it. The divided ends terminate, near the soil, in flexible points *x x*, for their passage under prostrate or leaning stalks. Near the upper end of the platform are holes *d d* to receive severed corn-ears, and, at the crotch of the slot *b*, vertical knives. *D D* are two loose pulleys, set flat upon the platform, one upon each of the lower points of the "divisions" of the same. These have each a flange on the periphery next to the platform to carry the edge of the chain, and are each pivoted upon a movable or adjustable axle, whose shank *e* ends in a slot to receive an adjusting bolt or screw, which connects each with the platform. There are placed near these pulleys, just at the expansion of the slit *b*, two anti-friction rollers,

f f, set vertically on the platform, to obtain the angular motion and opening of the chain at this point. *E E* are two pulleys on short shafts passing through the platform at its upper extremity. They are in a line transversely of the latter, and about the same distance apart as the sides of the slot *b*, and are provided with lugs or teeth to pull the chain. The axles of said pulleys each carry a pinion, *h*, which engages with another pinion, *g*, on the driving-shaft *K*. The latter has journals at either end, attached to lower side of platform, and is rotated by a pulley, *i*, on the end next to the wagon, and a band running to an endless-chain wheel, *J*, on the face of the rear wheel of the wagon. *F F* are two endless chains, each passing around one of the pairs of pulleys *D E*, and along one side of the slot. They are composed of metal links *k*, which are here and there extended into vertical knives *l*, which may be otherwise made removable to sharpen them; and between them short horizontal arms, lugs, or pushers *m*, formed by extending a link—which projects over the edge of the trough *G*—to push upward the severed corn ears.

These chains may be constructed of links of various fashions of rubber bands, wire ropes, ropes, or any similar bands, with attached or detachable knives, lugs, pushers, or knockers, or similar devices, for taking off the ears from the stalks.

Between the chains, at the head of the slot *b*, are placed erect knives *o o*, as auxiliaries to the knives, &c., upon the chains. *G G* are shallow troughs attached to the platform, one being between each chain, and extending from near the lower pulleys *D D* up to the corn-receiving holes *d d*, into which they open. *H H* are two parallel rubber or other soft rollers, or rollers with very fine teeth, extending across the inferior side of the platform beneath the holes *d d*. They are inclosed in a box, *p*, and geared, at the ends, by pinions *v w*, to turn toward each other to catch the husk from the ears. One of said pinions is rotated by a pinion on the hackling-roller *I* beneath. The box opens at one side into a spout, *q*, which drops the husked ears into the wagon *A*. *I* is a roller, provided with tearing or cutting teeth, and

placed close under and parallel with the husking-rollers H H just described, and pivoted in a similar manner in the ends of the same box p, and carrying a pinion, r, which drives the latter rollers H H; and a pulley, s, by which itself is driven by means of a chain or band from another pulley, t, on the shaft K, which drives the chain-pulleys E E. A slit or slot, u, in the rear of the box p, allows the ejection of the hackled husks into an attached bag or other convenience. Along the bottom of the box p is set a line of upright teeth to act with the roller-teeth in slitting the husks. These or similar teeth may be arranged throughout the curved surface of the box next to this roller.

The operation of this machine is as follows: The wagon A (any common wagon) to which the machine is attached is drawn in the direction which brings the lower points of the platform B on either side of a row of cornstalks, (standing, or bent, or prostrate,) which latter, passing into the slot b, the corn-ears are caught, and severed or taken off by the knives l or pushers m on the chains F F, running upward on either side of the slot. The ears, falling into the troughs G G on either side, are pushed up the same by the pushers into the holes d d, where they fall upon the rollers H H, which, revolving toward one another, tear off the husk, while the ears pass along the rollers into the spout q, and are dropped into the wagon. The husks, passing between the rollers H H, are caught, as fast as they protrude, by the teeth or knives of the contiguous hackling-roller I at the bottom of the box p, whence they are expelled, through a horizontal slit or opening in the back of the latter, into a proper receptacle, as a bag or similar device, to be removed as fast as filled.

At the crotch or head of the slot b, between the divisions of the platform B B, is stationed a vertical knife, o, or knives o o, in a line with each chain, to act with the latter in severing such

ears as may possibly have escaped gathering by the single knives or the pushers.

The whole is driven by an endless-chain wheel attached to the face of the rear wheel of a common wagon, a chain or band passing thence over the pulley i at the end of the uppermost shaft K, which, by its one or more pinions, g g, moves the chains simultaneously with the husking or hackling rollers, the last by means of a band from a pulley, t, on the outer end of this shaft running to the pulley s at the end of the hackling-roller I.

What I claim as my invention is—

1. The combination of endless chains F F, husking-rollers H H, and toothed cylinder or roller I, substantially as and for the purpose set forth.
2. The combination of the inclined platform B, provided with the endless chains F F, with the body of a wagon by means of the bar or brace C and clamps a, substantially as set forth.
3. The combination of the troughs G G with inclined platform B and endless chains F F having pushers m, substantially as set forth.
4. The combination of the fixed vertical knives o o with the platform B and the endless chains F F, substantially as set forth.
5. The inclined platform B, carrying the endless chains F F, having knives, knockers, or pushers, and provided with slot b, troughs G G, fixed knives o o, slots or holes d d, husking-rollers H H, toothed cylinder I, and spout q, in combination with a brace, C, and clamp for attaching the whole to the body of a wagon, substantially as set forth.

In testimony that I claim the foregoing corn-picking, husking, and hackling machine I have hereunto set my hand this 15th day of March, A. D. 1873.

EDMUND W. QUINCY.
